UNITED STATES PATENT OFFICE.

JOSEPH REICHL, OF KANSAS CITY, MISSOURI, ASSIGNOR TO DEAN HOTEL COMPANY, OF KANSAS CITY, MISSOURI, A CORPORATION OF MISSOURI.

DISPLAY WINDOW.

1,416,875.

Specification of Letters Patent. Patented May 23, 1922.

Application filed July 12, 1920. Serial No. 395,659.

To all whom it may concern:

Be it known that I, JOSEPH REICHL, a citizen of the United States, residing at Kansas City, in the county of Jackson and 5 State of Missouri, have invented certain new and useful Improvements in Display Windows; and I do declare the following to be a full, clear, and exact description of the invention, such as will enable others skilled 10 in the art to which it appertains to make and use the same, reference being had to the accompanying drawings, and to letters and figures of reference marked thereon, which form a part of this specification.

15 This invention relates to display devices and one of the objects thereof is to provide a window display which will have an attractive appearance and which will be capable of displaying articles in simulation of 20 a picture or painting, the background of which may be changed from time to time to correspond to the articles displayed.

Means is also provided for providing illumination within the confines of the display 25 device, the light sources being within grooves or recesses in the walls of the display device and preferably provided with a reflector so that beams of light may be directed upon the objects to be displayed, the light sources 30 being not visible from the front of the display device.

In the drawings,

Fig. I designates a front, elevational view 35 of a display device constructed in accordance with my invention, showing the articles therein on display.

Fig. II is a sectional view on the line II-II of Fig. I.

Fig. III is a perspective view of a movable panel, and

Fig. IV is a similar view of a supplemental panel.

In carrying out the invention I provide 45 a support, which may be the wall of the building or any other suitable support. The support is designated 1 and is provided with a recess 2, the front portions of which are flared to receive a simulation of a picture frame 3 of appropriate design, on the front 50 of which may be provided a glass window or panel 4. Supported upon the floor of the recess 2 is a stand 5 of any appropriate construction, over which may be placed, if desired, a drapery 6, and upon which may be 55 supported the articles to be displayed.

The rear wall of the recess 2 is provided with a removable panel 7, on which may be printed, painted or otherwise fixed scenery or fanciful designs, as at 8, the panels being interchangeable to provide backgrounds 60 or scenery appropriate to the articles to be displayed, and the panel 7 may be removably secured to the rear wall 9 of the recess by fastening devices 10 of appropriate construction. A supplemental wall 11 is provided in rear of the wall 9 and it is provided with a removable door 12, which may be fastened thereto in any appropriate manner.

A source of illumination is provided for the display devices, illustrated as consisting 70 of a recess or groove 13, extending around the walls of the recess and preferably the vertical walls and top wall, and said recess may be provided with a suitable reflector 14 for the lamps or other suitable light sources 75 15. The reflector is so designed that beams of light will be directed across the recess to provide a sheet or beam of light illuminating the portion of the recess in front of the background 7 so that the articles on display 80 will be illuminated while the rear of the recess will have a subdued light, thus bringing the articles to be displayed out more prominently to the attention of the observer.

It will be apparent that when it is desired 85 to re-arrange the display window or recess, it will be only necessary to remove the doors 12 and 7 and, after arranging the articles to be displayed, a door or panel 7 may be applied which will be appropriate to the articles to be displayed. For example, one background 7 may contain a simulation of flowers, another of scenery, etc., dependent upon the articles to be displayed in the recess 2.

What I claim and desire to secure by Letters-Patent is:

In a display device, a structure having a recess forming a sight opening and a front edge simulating a picture frame, a back for the recess having a picture thereon, an article-supporting stand between the frame and the back, the walls of the recess being grooved to house lighting devices, lighting devices in said grooves, and reflector devices in said grooves directing rays from the lighting devices over the article-supporting stand and restricting said rays from the back picture.

In testimony whereof I affix my signature.
JOSEPH REICHL.
